UNITED STATES PATENT OFFICE.

HERMAN R. SMITH, OF BROOKLYN, NEW YORK, AND ALBERT E. TWIST, OF CLIFTON, NEW JERSEY, ASSIGNORS TO RAYMOND CONCRETE PILE COMPANY, OF NEW YORK, N. Y., A CORPORATION OF NEW JERSEY.

COMPOSITE PILE.

Application filed August 30, 1922. Serial No. 585,129.

To all whom it may concern:

Be it known that we, HERMAN R. SMITH and ALBERT E. TWIST, both citizens of the United States of America, residing, respectively, at Brooklyn, Kings County, State of New York, and Clifton, Passaic County, State of New Jersey, have invented certain new and useful Improvements in Composite Piles, of which the following is a full, clear, and exact description.

This invention relates to composite piles, that is, piles composed of a lower wooden portion and an upper concrete portion. In such piles it sometimes happens that heaving of the ground due to driving adjacent piles causes the concrete upper portion to rise and separate from the lower. This vertical lifting force is so great that in some cases a separation of several inches between the concrete and the wood has been found. We have accordingly been led to devise our present invention, which has for its chief object to provide a simple and effective method of locking the two parts together so that they cannot separate under the conditions mentioned. To this and other ends the invention consists in the novel features hereinafter described.

In carrying out the invention in the preferred manner the two parts of the pile are locked by means of one or more vertical rods, the lower ends of which are securely fastened in the top of the wood. The rods themselves extend up into the shell in which the upper, concrete, portion is cast, and are shaped in such manner that when the concrete is deposited in the shell and hardens therein the rod or rods will be firmly gripped by the concrete, thereby positively preventing any upward movement of the concrete portion relatively to the lower wooden portion.

One form of our improved pile is illustrated in the accompanying drawing, in which

Fig. 1 is a vertical or longitudinal section at the joint between the wood and the concrete, showing the preferred method of securing the locking rod to the wood.

Fig. 2 is a section at the top of the concrete portion of the pile, showing convenient means for preventing separation before the concrete has set.

In the embodiments illustrated the lower or wooden portion of the pile is designated 55 by the numeral 10. As shown, it is formed with a neck or upward extension 11 of reduced diameter, which is encased in the concrete upper portion 12, cast in place in the usual shell 13, reinforced by the spirally or 60 helically arranged wire 14.

In the top of the wood pile 10 is a downwardly extending hole 15 of suitable depth, containing a tubular socket member 16, which is threaded on the inside to receive the 65 threaded lower end of the locking rod 17. The socket member is secured in place by a steel or iron locking pin 18 in the transverse bore or passage 19. The locking rod is twisted, roughened, or otherwise suitably 70 fashioned to give the concrete a firm grip, so that when the concrete has set, the two parts of the composite pile will be positively locked together. The members 16, 17 and 18 are preferably made of steel. 75

Around the lower end of the concrete pile is a sheet metal shoe 20, which is made small enough to require forcing it down over the neck or shank 11. In its final position the inner edge 21 bites into the wood and thus 80 aids in preventing separation of the two parts of the pile. If desired, the lower part of the concrete portion may be further protected and strengthened by an outer sleeve 85 22, in which case the lower end of the sleeve may extend up on the inner surface of the shoe, thus strengthening the lower part of the latter. The bottom of the sleeve is somewhat larger in diameter than the shoe, and hence has a spreading effect on the 90 shoe, which rocks the upper inside edge of the shoe inwardly, thus causing the pressure of the shoe to be concentrated at the point 21. This insures a firm grip by the shoe at the point mentioned. The sleeve extends 95 up the pile for two or three feet, firmly securing the main shell 13 and the boot 20 together, and thereby forming a water-tight and rigid connection between these two members. Also, as the shoe is forced down 100 on the shank of the wooden pile the two conform to each other so closely that in most cases the joint between them is tight enough to exclude water and thus prevent seepage upwardly between the concrete and the 105 wood.

As stated above, the concrete portion of our pile is, preferably, cast in place. This requires that in the driving operation the shell 13 must be supported by a removable core, as is customary. If the space available is sufficient, the shell and core can be assembled on the wood pile (the socket member 16 and key 18 being first inserted), and the whole can then be driven together. Usually, however, the wood pile is driven first, leaving the shank projecting above the ground, after which the shell and core are arranged on the wood pile and the driving continued until the shell is sunk to the desired depth.

15 When the wood pile and the shell have been sunk, the core is withdrawn and the locking rod 17 is then inserted and screwed home in the socket piece 16, after which the concrete is poured into the shell. If the locking rod is not long enough to be grasped at the top of the shell it may be screwed into place by means of a wrench or other suitable tool long enough for the purpose.

In the type of construction illustrated the 25 shoe and sleeve at the bottom of the concrete part of the pile are so connected as to be in effect one. This is a highly advantageous feature, as it provides a slip-joint between the shell and the shoe. When the shell is 30 driven and the core removed, the heaving of the ground before the concrete is deposited in the shell is sometimes sufficient to lift the shell. Ordinarily the shoe grips the shank or tenon of the wooden pile firmly enough 35 to hold the shoe and sleeve, in which case the shell simply rises in the latter, but the sleeve, held down by the shoe, prevents the opening of a gap at the bottom of the shell. This insures, in practically all cases, that 40 mud and water will be excluded from the shell and that when the concrete is deposited it will find its way down as far as the shoulder around the base of the shank.

If the heaving of the ground and consequent lifting of the shell occurs before the concrete has set enough to take an effective grip on the locking rod, the body of concrete is sometimes lifted also, thus separating from the wooden pile at the top of the shank. 50 Where the ground conditions are such as to exert a lifting pressure of the character described we prefer to use a locking rod long enough to extend above the surface of the concrete, and on the rod we fasten an abutment to hold the concrete down. Thus in Fig. 2 an abutment is shown at 25, held on the locking rod 17 by a removable collar 26 having a set screw 27. The abutment may be a disk of metal or wood, but in some 55 cases a piece of plank, say two inches thick and ten or twelve inches wide, is sufficient. If, now, the shell is lifted it will rise around the concrete, the latter being held by the abutment and locking rod. When the concrete has set the abutment is removed.

It will be observed that the upward pressure produced on the concrete section by heaving of the ground is taken in tension by the locking rod; and that the forces transmitted to the socket piece and key are 70 taken as shearing stresses, which the parts named are well able to withstand even though these parts are relatively small and light. Moreover, the metal parts of the lock are so well covered with concrete that the 75 joint is practically permanent. The locking rod also strengthens the concrete structure by serving as a reinforcement, giving the pile greater resistance, for example, to transverse stresses due to any tendency of the 80 ground to slide or slip.

It is to be understood that the invention is not limited to the structure herein specifically illustrated and described but can be embodied in other forms without departure 85 from its spirit.

We claim—

1. A composite pile comprising a lower wooden portion and an upper concrete portion, a socket member fastened in the top 90 of the wooden portion, and a locking rod fastened at its lower end in the socket member and having its upper portion embedded in the concrete.

2. A composite pile comprising a lower 95 wooden portion and concrete upper portion, a socket member in the upper end of the wood portion, a transverse key extending through the socket member to fasten the same in place, and a locking rod embedded 100 in the concrete upper portion and having its lower end secured in said socket member.

3. In a composite pile, a wooden lower portion having an upwardly extending shank, a concrete upper portion embedding 105 said shank and having on its lower end a shoe firmly embracing the said shank, and means embedded in the concrete upper portion and cooperating with the shank to lock the parts of the pile together against longitudinal separation.

4. In a composite pile, a wooden lower portion, a concrete upper portion enclosed in a shell, a longitudinal locking member embedded in the concrete portion and anchored 115 to the wooden portion, and means connected to the locking member to hold the concrete down when the shell is raised by heaving of the ground before the concrete has set.

5. In a composite pile, a wooden lower 120 portion, a concrete upper portion enclosed in a shell, a longitudinal locking member anchored to the wooden portion and extending upwardly into the concrete, and means removably mounted on the locking member at 125 the top of the concrete to hold the latter down when the shell is raised by heaving of the ground before the concrete has set.

6. In a composite pile, a wooden lower portion, a concrete upper portion, a shell 130

surrounding the concrete and having a slip-joint adjacent to the wooden portion to prevent formation of an opening for the entrance of mud or water when the upper portion of the shell is raised by heaving of the ground, a locking member embedded in the concrete and anchored to the wooden portion of the pile, and means connected to the latter member to prevent upward movement 10 of the concrete when the shell is raised by heaving of the ground before the concrete has set.

7. In a composite pile, a wooden lower portion, a concrete upper portion enclosed 15 in a shell, a longitudinal locking member embedded in the concrete portion and anchored to the wooden portion, and a transverse abutment on the upper end of the locking member to hold the concrete down when 20 the shell is raised by heaving of the ground before the concrete has set.

8. In a composite pile, a wooden lower

portion, a concrete upper portion enclosed in a shell, a locking member anchored to the wooden portion and extending upwardly 25 through the concrete, and an abutment removably mounted on the locking member above the concrete to hold the latter down when the shell is raised by heaving of the ground before the concrete has set.

9. In a composite pile, a wooden lower portion, a concrete upper portion, a longitudinal locking member secured to the wooden portion and extending upwardly into the concrete, and a transverse abutment carried 30 by the upper part of the locking member to hold the concrete down against heaving action of the ground before the concrete has set.

In testimony whereof we hereto affix our 40 signatures.

HERMAN R. SMITH.
ALBERT E. TWIST.
